UNITED STATES PATENT OFFICE.

EDGAR B. STOCKING, OF WASHINGTON, DISTRICT OF COLUMBIA; SARAH C. STOCKING
EXECUTRIX OF SAID EDGAR B. STOCKING, DECEASED.

REVERSE POWER-ACTUATED RELEASE FOR CLOTHES-WRINGERS.

1,322,369.

Specification of Letters Patent. Patented Nov. 18, 1919.

Application filed March 2, 1917. Serial No. 152,035.

To all whom it may concern:

Be it known that I, EDGAR B. STOCKING, a citizen of the United States, residing at Washington, in the District of Columbia,

5 have invented certain new and useful Improvements in Reverse Power-Actuated Releases for Clothes-Wringers, of which the following is a specification, reference being had therein to the accompanying drawing.

10 This invention has relation to clothes wringers and one of its main objects is to provide means for quickly releasing the pressure existing between the wringer rolls when in operation by manipulating the handle or crank by which the rolls are driven.

15 Another object is to restore the pressure by means of the handle or crank.

Another object of the invention is to embody it in such devices as can be readily 20 applied to an ordinary wringer without changing any of its principal parts in any material respect.

Another purpose in view is to avoid a readjustment of the pressure screws after a 25 release of the pressure between the rolls.

Other objects and advantages of the invention will appear in the following description and the novel features thereof will be particularly pointed out in the claims.

30 In the accompanying drawing, in which like parts are indicated by like numerals:

Figure 1 is a feed-side elevation with a central portion broken out and portions in vertical section of an ordinary wringer to 35 which the invention is applied, the pressure being on.

Fig. 2 is an end elevation of Fig. 1, the crank shaft being in section.

Fig. 3 is a similar end elevation, the parts 40 being in the positions assumed when the pressure is released and also in position to restore pressure.

Fig. 4 is a detail in perspective of an end-less track or guide for the resetting device.

45 In the drawing I have shown an ordinary wringer comprising standards 1, in which is mounted a roll 2 adapted to be driven by a crank or handle 3 mounted on the shaft of the roll which drives in turn the upper roll

50 4 through the medium of the gears 5. The rolls are held under pressure by a spring 6

through the medium of a cross bar 7 carrying pressure screws 8 for adjusting the pressure in the usual manner of clothes wringers of this type now in use.

55

In the following description the usual known construction of a quick release comprises the movable cross-bar, screws and springs and some device such as a hook or a keeper associated with the cross-bar to hold or retain the pressure and such elements are herein included in the term pressure device, and with some releasing device 60 constitute an operative structure.

The invention comprises a pressure device 65 9 which in this instance is a rigid plate secured to the end of the cross-bar 7 and is limited in its downward and upward movements by a pin or pins 10 seated in the standard and arranged within a recess or 70 recesses 11 formed in the edge or edges of the device 9. Said device also is provided with a pin 12 with which a hook or pressure releasing device 13 cooperates to retain pressure and to release the same as hereinafter 75 described.

The hook 13 is pivoted preferably below the lower gear and at a point in line with the pin 12 as at 14 to preserve alinement and to reduce the friction of device 9 upon 80 the pin or pins 10 which would occur were the hook 13 pivoted elsewhere. Between its pivoted and free ends the hook is provided with an extension 15 against which an arm 16 of a pawl 17 contacts; the pawl being 85 pivoted on the standard at 18 and projecting into the path of the teeth of the lower gear 5 while a spring 19 keeps the pawl in operative relation with said gear.

In the shaft of the lower roll 2 is a pin 20 90 and in the inner face of the hub of the crank or handle 3 is a recess 21 which embraces said pin and preferably extends from one quarter to one-third of the circumference of the hub. The recess 21 is the only change 95 made in some wringers as a pin and pin-slot are common means for mounting a handle on a shaft in some wringers. A recess as 21 gives the handle or crank a limited movement without rotating the shaft and roll.

100 Upon the plate 9 there is pivoted at 22 a resetting lever 23 comprising a lateral arm

24 the main body 23 thereof being disposed at an angle to said arm and is provided with a pin 25 and a tooth 26 and terminates at its free end in a cam or inclined face 27 which 5 cam though preferred is not absolutely essential.

In the standard are seated obstructions in the form of pins 28-29 and 30 arranged to coöperate with the resetting lever as hereinafter described.

An endless track or guide 31 is located upon or in the standard to receive the pin 25 of the resetting lever 23 and comprises an unobstructed rectangular continuous passage 32 adapted to give the free end of the resetting lever 23 a four direction movement. While the track or guide may be formed in the standard it is preferable to form it of metal and set it in the standard 15 and secure the same by suitable means as screws in a flange 33 formed thereon.

The operation of the invention is as follows:

Assuming the parts to be under pressure 25 as shown in Figs. 1 and 2, the operation of wringing clothes takes place by rotating the roll 2, in the direction indicated by the arrow in Fig. 2, the recess 21 in the hub of the handle or crank pressing against what 30 would be the lower side of pin 20 in Fig. 1 and the pawl 17 riding inoperatively over the teeth of the gear 5 the arm 16 of the pawl vibrating inoperatively between the extension 15 and the body of the hook 13. 35 Now in case of abnormal feeding or of the entrance of the fingers or hand of an operator between the rolls the natural act of reversing the crank carries the opposite end of the recess 21 against the opposite side of 40 the pin 20 and instantly pushes the pawl 17 downwardly and the arm 16 outwardly against the extension 15 forcing the hook 13 against the tension of spring 34 off from the pin 12 of the device 9 when the upper 45 roll 4 is instantly released from the pressure of the springs 6. It will be noted that in this natural reversal of the handle or crank the hand or fingers of the operator are only subjected to a rolling pressure when 50 being released by reason of the recess 21 which permits said reversal without rotating the shaft or the roll in a direction to draw the fingers between the rolls so that instant release of pressure is obtained without causing increased pain or injury.

During the release of pressure just described the resetting devices have been put in position to be operative simply by resuming rotation of the crank as in wringing.

60 By reference to Fig. 2 the parts being under pressure it will be seen that the pin 25 of the lever 23 is at the lower end of the outside vertical track of the guide 31, and that it is held there by the contact of the arm 24 with the pin 29. As hook 13 is forced

from pin 12 of device 9 said device rises with the cross-bar 7 and carries with it upwardly free from contact with gear 5 the resetting lever 23, the pin riding in the vertical outside track. As the arm 24 strikes 70 pin 28 it forces pin 25 inwardly along the upper cross track of guide and brings the tooth 26 of the lever into mesh with the gear as shown in Fig. 3. Now by turning the crank in the direction of wringing the 75 resetting lever draws down device 9 and the cross-bar, the pin 25 riding the inner vertical track, thus holding the tooth in mesh with the gear, until the spring 34 forces the hook 13 over the pin 12 when the pin 29 contacting with the lower edge of arm 24 causes pin 25 to ride outwardly in the bottom cross track of the guide thus forcing tooth 26 out of mesh with gear 5. Simply to insure this movement of the pin 25 and 80 free the tooth of the lever 23 from the gear the cam face 27 and pin 30 are provided.

In the above manner and by the above means a release and resetting of pressure is accomplished by a simple and natural reversing 90 of the handle crank of an ordinary wringer. It is understood of course that the means above described are duplicated at each end of the wringer so that, by means of operative connection with the gear at each 95 end of the roll which gear is nonrotatably secured to the roll, both ends of the upper roll are relieved of pressure simultaneously. It is apparent that the invention is applicable to power driven wringers which are provided with any well known reversing means.

What I claim is:

1. A clothes wringer comprising a frame having movable pressure rolls and pressure means for said rolls, retaining means for said movable pressure means, a pressure releasing device for said retaining means, gearing for driving said rolls and a connection between said gearing and said releasing device operated by a reversal of the rotation of 105 said gearing for actuating said releasing device.

2. A clothes wringer comprising a frame having pressure rolls and movable pressure means for said rolls, means for driving said 115 rolls, a pressure release for said movable pressure means, said release being operated by said gearing, means for rotating said gearing, said means being provided with means for allowing a limited movement 120 thereof.

3. A clothes wringer comprising a frame having pressure rolls and movable pressure means for said rolls, a pressure release for 125 said movable pressure means, a resetting device for said pressure release, a gear and means for alternately operatively connecting the release and the resetting device with said gear.

4. A clothes wringer comprising a frame 130

- having pressure rolls and pressure means for said rolls, pressure retaining means for holding said pressure means in predetermined position, a release for said pressure retaining means, a resetting device moved into operative position by said release, a gear for driving one of said pressure rolls, and means for alternately operatively connecting the release and the resetting device with said gear. 5
- 10 5. A clothes wringer comprising a frame having pressure rolls and pressure means for said rolls, a gear for driving one of said rolls, a pressure release and a pivoted connection between said release and gear for moving said pressure release in position to release said pressure means. 15
6. A clothes wringer comprising a frame having pressure rolls and pressure means for said rolls, a gear for driving one of said rolls, a pressure release pivoted in line with the pressure means having a detachable connection therewith and operative connection between said gear and release. 20
7. A clothes wringer comprising a frame having pressure rolls and pressure means for said rolls, a pressure release, a gear for driving one of said rolls, means for reversing the rotation of said gear and operative connection between said release and said gear. 25
- 30 8. A clothes wringer comprising a frame having pressure rolls and pressure means for said rolls, a gear for driving one of said rolls, means for rotating said gear, a pressure release, and means operated by the reverse movement of said gear for actuating said pressure release. 35
9. A clothes wringer comprising a frame having pressure rolls and pressure means for said rolls, a top bar having means for adjusting said pressure means, hooks for holding said top bar in predetermined position within said frame, a gear for rotating one of said pressure rolls and means operated by the reversal of said gear for moving said hook out of engagement with said top bar for releasing said pressure means. 40
- 45 10. A clothes wringer comprising a frame having pressure rolls and pressure means for said rolls, a top bar having means for adjusting said pressure means, hooks for holding said top bar in predetermined position within said frame, a gear for rotating one of said pressure rolls, means operated by the reversal of said gear for moving said hooks out of engagement with said top bar for releasing said pressure means, and a resetting device for said pressure releasing means. 50
- 55 60 11. A clothes wringer comprising a frame having pressure rolls and pressure means for said rolls, a gear and shaft for one of said rolls, a pin carried by said shaft, a crank having a hub provided with a recess 65 to receive said pin, a release for said pressure means having a pawl coacting with said gear for actuating the release on the reversal of said gear, and a resetting device moved into position by said release to operate with said gear. 70
12. A clothes wringer comprising a frame having pressure rolls and pressure means for said rolls mounted therein, a top bar having means for adjusting said pressure means, plates carried by said top bar, shafts 75 for said rolls, meshing gears carried by said shafts, means for driving one of said shafts, pivoted hooks engaging with the plates of the top bar, and means actuated by one of said gears on the reverse movement thereof for moving said hook in position to release said top bar. 80
13. A clothes wringer comprising a frame having pressure rolls and pressure means for said rolls mounted therein, a top bar 85 having means for adjusting said pressure means, plates carried by said top bar, shafts for said rolls, meshing gears carried by said shafts, means for driving one of said shafts, pivoted hooks coacting with the plates of 90 the top bar, means actuated by one of said gears on the reverse movement thereof for moving said hooks in position to release said top bar, and means actuated by said gear for resetting said top bar. 95
14. A clothes wringer having a pressure applying means, movable means for holding said pressure applying means in predetermined position, means for actuating said movable members by a reversal movement 100 of the pressure rolls thereof, and means actuated by the forward movement of said rolls for resetting said pressure means. 105
15. A clothes wringer comprising a frame having pressure rolls and pressure means for said rolls mounted therein, shafts for 110 said rolls carrying meshing gears, a top bar movably mounted in said frame having means for adjusting said pressure means, plates carried by said top bar, pins carried 115 by said plates, pivoted hooks arranged to engage said pins, a crank for driving one of said shafts, means actuated by the movement of one of said gears in one direction, for moving said plates in position to be engaged by said hooks, and means actuated by the movement of said gear in a reversed direction for moving said hooks out of engagement with said plates for releasing said pressure means. 120
16. A clothes wringer comprising a frame having pressure rolls and pressure means for said rolls, means for driving said pressure rolls, means actuated by said driving means for moving said pressure means in 125 position to exert pressure upon said rolls, and means operated by a reversal movement of said driving means for releasing said pressure means. 130
17. A clothes wringer comprising a frame

having pressure rolls and pressure means for said rolls mounted therein, a top bar movably mounted in said frame, hooks for holding said top bar in predetermined position within said frame, gears carried by the shaft of the lower roll of said wringer, and pawls mounted on said frame coacting with said gears and said hooks for moving

said hooks in position to release said top bar on a reversed movement of said shaft. 10

In testimony whereof I hereunto affix my signature in the presence of a witness.

EDGAR B. STOCKING.
